Alexander Block

UNITED STATES PATENT OFFICE.

ALEXANDER BLOCK, OF NEW YORK, N. Y.

LOCK.

1,344,613.

Specification of Letters Patent. Patented June 29, 1920.

Application filed December 30, 1919. Serial No. 348,266.

To all whom it may concern:

Be it known that I, ALEXANDER BLOCK, a citizen of the United States, and resident of the city of New York, in the county of New York and State of New York, have invented certain new and useful Improvements in Locks, of which the following is a specification.

This invention relates to locks, and more particularly to locks which may be used upon swinging or sliding doors, either of which type of doors may be securely locked by means of the lock described herein, with the possibilities of its being picked, jimmed or otherwise dislocated by a burglar reaching thereto with a jimmy through the exterior of the door, reduced to a minimum.

In the lock embodying my invention, I have provided a bolt and actuating means of simple construction, the initial step during the progress of locking the door being to move said bolt longitudinally into the keeper. The next step in the locking operation is to move said bolt in a direction to force a projection or hook on the outer extremity thereof into engagement with said keeper, thus interlocking the lock casing with said keeper.

Other objects and advantages will be pointed out and still others become apparent in the specification and claims.

In the accompanying drawings, Figure 1 shows a sectional elevation of the lock showing the disposition of its parts when in unlocked state. Fig. 2 is a sectional elevation of said lock showing the disposition of its parts during the initial locking movement. Fig. 3 is a sectional elevation showing the disposition of the parts of the lock when the locking operation has been completed. Fig. 4 is a sectional plan view of the lock shown in Fig. 3.

The lock body proper comprises a metal casing, 1, and locking mechanism contained therein; said casing being secured to a door by means of screws. Keeper, K, is secured to door frame DF also by means of screws. The door may be unlocked from the inside by turning a knob, N; and from the outside by inserting key S in tumbler barrel T of the locking mechanism which passes through the door D. The keeper K is fitted onto the door frame DF, so that its outer surfaces are flush with the surfaces of the frame. During the unlocked state, bolts, 10^A—10^B are positioned in the casing, the faces of the

outer extremities of said bolts being flush with the edge of the lock casing. Said bolts being preferably rectangular in shape are provided with projections or hooks 10^H—10^{H'} on their outer extremities. At their inner ends said bolts are pivoted on a frame or plate 2 on studs 30—31; said inner ends respectively embracing stop projections 32—33 abutting on studs 15—15^a respectively. A link, 9, is pivoted by one end to one of the bolts and by its other end to the other bolt, thus yieldingly connecting said bolts, and rendering it possible to transmit movement from one of said bolts to the other. A spring 8 mounted on plate 2 bears down on said bolts and normally maintains their stop projections 32—33 in abutment with stops 15—15^a respectively, and normally tends to move the bolts 10^A—10^B out of engagement with the keeper subsequently to the locking operations. The frame or plate 2 is or may be provided with a groove or grooves fitting over a horizontal track—not shown—cast upon the wall of casing 1, and thus guided in its horizontal movement; studs may also be provided for guiding said frame and thereby the bolts at all sides against lateral displacement and they may be therefore shifted in a direction toward or away from the keeper, as shown in Figs. 1, 2 and 3.

A tumbler pawl 4 is pivoted upon frame 2 at 2^b and is provided with a projection 4^a normally bearing against a projection 2^a on frame 2, and also comprises a ledge 4^c abutting on a lug 17 and maintained in position by means of a spring 6 attached to its pivot head and leaning against a pin 6^a; by all of which means the bolts are maintained in their locked position. An arm 14 is mounted upon a sleeve 14^a revolvably mounted in casing 1; a knob N attached to said sleeve is adapted to rotate said arm 14 to bear against projection 4^a of pawl 4 and release ledge 4^c from lug 17, said arm then continuing in its further progress to impinge against a projection 2^b on frame 2 to move the bolts out of the lock casing into the keeper, when the tumbler pawl 4 descends to bring ledge 4^c into abutment with lug 17 to maintain said bolts in said position. To return bolts 10^A—10^B, the knob N is turned in the opposite direction when arm 14 is made to impinge against projection 2^a of frame 2 after releasing said frame by bearing against projection 4^a of tumbler pawl 4. Another arm

20 is mounted upon a spindle 20^a connected with tumbler barrel T operated from the outside of door by a key S, which when turned rotates arm 20 to the same purpose as knob 5 N on its arm 14—to shift the bolts 10^A—10^B into and out of the keeper.

This initial step in the locking operation, that is, the shifting of the bolts into the keeper, is accomplished by turning the knob 10 N or key S through approximately one half revolution. As said knob or key continues in its progress to complete its revolution, the respective arms, 14 or 20, actuate certain mechanism which bear upon bolts 10^A—10^B 15 to move them in a direction to force their vertical projections or hooks or secondary bolts 10^H—10^{H'} into recesses R and R² respectively provided for that purpose in the keeper and thus to interlock the casing 1 20 with keeper K. Said interlocking mechanism embraces a frame or plate 3 provided with a groove or grooves, not shown, fitting on track or tracks, not shown, cast on casing 1, for guiding said frame against 25 lateral displacement in its movement toward or away from keeper K. A tumbler pawl 5 is pivoted upon frame 3 at 5^b and comprises a projection 5^a normally bearing against projection 3^a on frame 3, a ledge 5^c on pawl 30 5 abuts on a lug 16 on casing 1, and a spring 7 attached to its pivot head is adapted to maintain pawl 5 in position, said spring leaning against pin 7^a. A lever 11 pivoted at 12 embraces an arm 11^a embracing a cam 35 rounded surface adaptable for bearing against bolt 10^B, and an arm 11^b to which is pivoted one end of a link 13, the other end of which link is pivoted to frame or plate 3. Any movement transmitted to said frame 40 3 will cause lever 11 to swing toward or away from the keeper depending upon the direction in which frame 3 is caused to move, and thus cause the bolts to move into engagement with the keeper a spring 8 being provided 45 to move said bolts out of engagement with said keeper after said bolts have been released by said lever.

To lock the door, the key or knob mechanism is turned through a complete revolution. While describing the first half revolution, arm 14 bears first on projection 4^a of tumbler pawl 4 and releases ledge 4^c from lug 17; the arm then bears against frame projection 2 and moves the bolts longitudinally into locking position. Subsequently to the locking operation, arm 14, in completing the revolution, first bears against tumbler pawl 5 to release ledge 5^c from lug 16, then bears against projection 3^a of 55 frame 3 and moves it in a direction to actuate lever or cam 11, to in turn cause said lever to bear against bolt 10^B and transmit said movement from said bolt to bolt 10^A through link 9 so that the bolts and their 60 65 hooks are moved into engagement with the

keeper. To unlock the door the motion is reversed.

Having thus described the invention, what I claim as new and desire to secure by Letters Patent, is:—

1. In a lock, the combination of a carrier, a plurality of hooked bolts movably mounted thereon, a link for yieldingly connecting said bolts, means for moving said carrier and said bolts in unison, and for subsequently moving said bolts independently on said carrier to project said bolts into engaging position, and means for locking the bolts against reverse movement when they are in said projected position. 80

2. In a lock, the combination of a lock casing, a carrier wholly confined within the casing, a plurality of hooked bolts movably mounted on said carrier, a link for yieldingly connecting said bolts, means for moving said carrier and the bolts in unison to deliver the bolts into locking position, and additional means for subsequently moving said bolts with reference to said carrier into engaging position, said means acting to prevent reverse movement of said bolts except by the instrumentality of said means. 90

3. In a lock, the combination of a lock casing, a carrier, a plurality of hooked bolts pivoted on said carrier, a link for yieldingly connecting said bolts, means for actuating said carrier to cause it to move the bolts into locking position, said carrier being wholly confined within the casing, and means for subsequently moving the bolts with reference to said carrier into engaging position, and for maintaining them in that condition. 100

4. In a lock, the combination of a lock casing, a plurality of hooked bolts, a carrier upon which said bolts are movably mounted, 105 a link for yieldingly connecting said bolts, means for moving the carrier and the bolts in unison, means being provided to prevent reverse movement of said carrier and said bolts except by the instrumentality of said means, and additional means for subsequently moving said bolts into engaging position, and for maintaining the bolts in said position.

5. In a lock, the combination of a carrier, 115 a plurality of hooked bolts movably mounted thereon, a link for yieldingly connecting said bolts, means for maintaining said bolts in normal position with reference to said carrier, means for moving said bolts and 120 said carrier in unison, and separate means for subsequently moving said bolts on the carrier into engaging position, said means acting to prevent the reverse movement of said bolts except by the instrumentality of 125 said means.

6. In a lock, the combination of a lock casing, a plurality of hooked bolts pivotally mounted thereon, a spring for maintaining said bolts in normal position with reference 130

- to said carrier, a link for yieldingly connecting said bolts, means for moving said carrier and the bolts in unison, and for subsequently moving the bolts on the carrier 5 against the action of said spring into engaging position, said means being adapted to maintain the bolts in that condition with the spring under tension.
7. In a lock, the combination of a lock casing, a carrier wholly confined therein, hooked bolts pivotally mounted on said carrier, a link for yieldingly connecting said bolts, a spring for maintaining the bolts in retracted rest position with reference to said 10 carrier, means for moving the carrier and the bolts in unison, said bolts projecting beyond the edge of the carrier, and additional means for moving the bolts on the carrier into engaging position against the action of 15 said spring, said means acting to prevent reverse movement of said bolts from their engaging position, and said spring causing said bolts to move away from their engaging position subsequently to the release of the 20 bolts by their maintaining means.
8. In a lock, the combination of a lock casing, a carrier, a plurality of hooked bolts movably mounted thereon, a link for yieldingly connecting said bolts, said carrier and 25 said bolts being adapted to move in unison into and out of locking position, means for moving said bolts into locking position, and a cam for subsequently reciprocating said bolts into engaging position, means for actuating 30 said cam and for causing said cam to maintain said bolts in their projected position.
9. In a lock, the combination of a lock casing, a carrier, a plurality of hooked bolts 35 movably mounted on the carrier, a link for yieldingly connecting said bolts, a spring for maintaining said bolts in normal position with reference to said carrier, means for moving said carrier and the bolts in unison, a cam, means for actuating said cam to cause it to move the bolts into engaging position against the action of said spring, said cam being adapted to maintain the bolts in 40 operative position with the spring under tension, and the spring for moving the hooked bolts out of the engaging position and into normal position with reference to 45 said carrier subsequently to the release of said bolts by said cam.
5. 10. In a lock, the combination of a lock casing, a carrier, a plurality of connected hooked bolts pivotally mounted thereon, means for moving said carrier and said bolts into and out of locking position, a lever 50 having a cam surface, said lever being pivoted on said casing, a cam actuator adapted for 55 slideable movement in said casing, said cam actuator being adapted to cause the lever to move said bolts on said carrier into 60 engaging position subsequently to the lock- 65

ing operation, and a spring for moving the bolts away from their projected position subsequently to the release of said bolts by said cam lever.

11. In a lock, the combination of a carrier, connected bolts movably mounted thereon, a stop projection on the inner end of each bolt, a stud on the carrier, said stop projection abutting on said stud when the bolts are in normal position with reference 70 to said carrier, a hook on the outer or locking end of each bolt, a lock casing, a keeper, means for moving said carrier and the bolts in unison into locking position in said keeper, said carrier being wholly confined 75 in said casing, and means for moving said bolts on said carrier subsequently to the locking operation, to reciprocate said bolts into engagement with the keeper and interlock the casing with said keeper, means being provided for maintaining said bolts in 80 said interlocking position.

12. In a lock, the combination of a carrier, yieldingly connected hooked bolts pivoted on said carrier, means for moving the 90 carrier and the bolts in unison, a lever having a cam surface for subsequently moving said bolts with reference to said carrier into engaging position, a frame adapted for actuating said lever, means for actuating said 95 frame, and means for maintaining the frame, the cam lever and the bolts in operative position.

13. In a lock, the combination of a carrier, yieldingly connected bolts, a hook on 100 the outer or locking end of each bolt, said bolts being movably mounted on said carrier, a lever having a cam surface, a lever actuating frame adapted for slideable movement in the lock casing, key or knob actuated mechanism for first moving said carrier and the bolts in unison, and for subsequently moving said lever actuating frame to force the lever to move the bolts on said 105 carrier into engaging position, means for maintaining said frame, said lever and said bolts in operative position, and a spring for moving said bolts out of their projected position subsequently to the release of said 110 bolts by said projecting means.

14. In a lock, the combination of a carrier, a plurality of hooked bolts, means for yieldingly connecting said bolts, said bolts being movably mounted on said carrier, a lever having a cam surface, a frame for 120 actuating said lever, a link connecting said lever with said frame, and key or knob mechanism for first moving said carrier and said bolts in unison, and for subsequently actuating said frame to force the cam lever 125 to move said bolts with reference to said carrier into engaging position, said key or knob mechanism being arranged to accomplish the locking operation while describing part of a revolution, and the interlock- 130

- ing operation while completing said revolution.
15. In a lock, the combination of a carrier, pivotally connected hooked bolts pivotally mounted on said carrier, key or knob mechanism for moving said carrier and the bolts in unison while said mechanism is describing part of a revolution, a lever having a cam surface, a frame for actuating said lever, and said key or knob mechanism for actuating said frame to force said lever to move the bolts with reference to said carrier into projected position during the completion of the said revolution by said mechanism subsequently to the locking operation.
16. In a lock, the combination of a carrier, a lock casing, a keeper, hooked bolts movably mounted on said carrier, means for pivotally connecting said bolts, a lever having a cam surface, a frame adapted for movement in said casing, and key or knob mechanism for causing said carrier to move the bolts into locking position in said keeper while said mechanism is describing part of a revolution, and subsequently to the locking operation, for moving said bolts with reference to the carrier into interlocking position while said key or knob mechanism is completing said revolution, and means acting to prevent reverse movement of said bolts excepting by the instrumentality of said key or knob mechanism.
17. In a lock, the combination of a carrier, hooked bolts pivotally mounted thereon, means for pivotally connecting said bolts, a lever having a cam surface, a frame for actuating said lever, a pawl on the carrier and a pawl on said frame, key or knob mechanism for first releasing said carrier and for moving said carrier and the bolts, and for subsequently releasing said frame and for actuating said frame to force said cam lever to move said bolts into engaging position, said pawl on the carrier and said pawl on the frame acting to prevent reverse movement of said carrier and the frame respectively and thereby maintaining the bolts firstly in locking position and then in engaging position respectively.
18. In a lock, the combination of a carrier, hooked bolts movably mounted on said carrier, a lever having a cam surface, a frame for actuating said cam lever, and key or

knob mechanism for moving said carrier and said bolts in unison, and for subsequently actuating said frame to cause said lever to move the bolts into engaging position, the cycle of movement of said carrier and bolts in unison occurring while said key or knob mechanism is describing part of a revolution, and the cycle of movement of said bolts into engaging position occurring while said mechanism is completing the revolution, means being provided for preventing reverse movement of said bolts except by the instrumentality of said key or knob mechanism.

19. In a lock, the combination of a carrier, a hooked bolt movably mounted thereon, means for maintaining said bolt in normal position with reference to said carrier, means for moving said carrier and the bolt in unison, a lever having a cam surface, and means for actuating said lever to cause the bolt to move with reference to said carrier into engaging position, said means acting to prevent the movement of said bolt away from its projected position except by the instrumentality of said means.

20. In a lock, the combination of a carrier, a hooked bolt pivotally mounted on said carrier, a lever having a cam surface, a frame adapted for slidable movement and for actuating said lever, and key or knob mechanism for primarily moving the carrier and the bolt in unison and for subsequently actuating said lever actuator to cause the lever to reciprocate the bolt into engaging position, means for maintaining the frame, the lever and the bolt in operative position, and means for moving the bolt out of its projected position subsequently to its release by said cam lever, said key or knob mechanism being arranged to move the carrier and the bolt in unison during the rotation of said mechanism through part of a revolution, and to move the bolt with reference to the carrier during the rotation of said mechanism through the remainder of said revolution.

In witness whereof I hereby affix my signature, in the presence of two witnesses, this 29th day of December, 1919.

ALEXANDER BLOCK.
